Henry E. Morton

By Bartholomew Bartholomew Attorneys

UNITED STATES PATENT OFFICE.

HENRY E. MORTON, OF MUSKEGON HEIGHTS, MICHIGAN.

TOOL-CARRYING ATTACHMENT FOR METAL-WORKING MACHINES.

Application filed March 23, 1923. Serial No. 627,015.

To all whom it may concern:

Be it known that I, HENRY E. MORTON, a citizen of the United States of America, residing at Muskegon Heights, in the county 5 of Muskegon and State of Michigan, have invented certain new and useful Improvements in Tool-Carrying Attachments for Metal-Working Machines, of which the following is a specification, reference being had 10 therein to the accompanying drawings.

This invention relates to tool carrying attachments for metal machines and more particularly to tool carrying heads of the character shown and described in my United 15 States Letters Patent numbered 1,206,884, dated December 5, 1916.

The object of the present invention is to increase the efficiency of heavy duty metal working machines by so constructing and arranging an attachment as to make the same applicable to the performance of a wide range of work and adaptable to effect tool 20 adjustments for various kinds of work.

A further object is to provide an arrangement whereby a plurality of tools is carried by a single head, said head being quickly adjustable to bring any one of the tools into operative position, and said tools being independently adjustable to the work. 25 It is also an object to provide certain other new and useful features in the construction and combination of parts, all as hereinafter 30 more fully described.

With the above and other ends in view, the invention consists in providing a head attachment for heavy duty metal working machines, whereby said head may be rotatively adjusted without detachment of the head from the machine and whereby the 35 head may be attached to or detached from the ram of a shaper with facility.

The invention further consists in certain other new and useful features and in other matters hereinafter set forth and more particularly pointed out in the appended claims, reference being had to the accompanying drawings, in which

Figure 1 is a side elevation of a device illustrative of the invention and showing the same as applied to a draw-cut shaper;

Fig. 2 is a front end elevation of the device detached;

Fig. 3 is a longitudinal vertical section substantially upon the line 3—3 of Fig. 2;

Fig. 4 is a rear end elevation of the de-

vice showing the same attached to a ram and the ram in section upon the line 4—4 of Fig. 3;

Fig. 5 is a detail view of a portion of the device showing a clapper box in transverse 60 section;

Fig. 6 is a detail view of a clamping ring showing a portion thereof broken away and in section;

Fig. 7 is a similar view of a drum showing 65 portions thereof broken away and in section;

Fig. 8 is a sectional detail through locking mechanism substantially upon the line 8—8 of Fig. 2; and

Fig. 9 is a sectional detail through a frictional holding mechanism, substantially upon the line 9—9 of Fig. 2.

As illustrative of an application of the invention, in Fig. 1 of the drawings, a portion of a draw-cut shaper of an old and well known construction is shown, the frame of the shaper being indicated at 1 and the work holding bed which is positioned at the forward side of the frame is indicated at 2. The usual reciprocating ram 3 is carried by the frame and extends horizontally above the bed 2, said ram being reciprocated by the usual drive mechanism (not shown), and being adapted to carry cutting tools upon its free end for operating upon the work which is secured in place upon the bed below. Further description of the draw-cut shaper is deemed unnecessary as it forms no part of this invention, this invention relating particularly to a tool carrying device or head adapted to be attached to the externally screw-threaded forward end of the ram of shapers where the cutting tool is reciprocated by the ram relative to the work or said head may be applied to other forms 85 of heavy duty metal working machines, such as planers wherein the work is reciprocated relative to the milling tool or tools. 90

The tool carrying device or head, illustrative of the present invention, comprises a circular drum 4 which is formed at its lower side with a half bearing 5 to engage the end of the ram, said half bearing being internally screw-threaded to engage the screw-threads formed on the end of the ram. 105 Within the drum 4 is a detachable half bearing 6 to engage the upper side of the screw-threaded end of the ram, said half bearing being also internally screw-threaded, and this half bearing is detachably secured with- 110

in the drum by means of stud bolts 7 (see Fig. 4) on the drum at each side of the half bearing 5 to engage openings in ears 8 on the sides of the detachable half bearing 6, 5 nuts being provided on the studs to engage the ears and force the movable half bearing into engagement with the ram and toward the half bearing on the drum. The half bearing 6 is further secured to the 10 drum by means of bolts 9 carried by the drum and extending through vertical slots 10 in an upwardly extending bracket portion 11 which is formed integral with the half bearing 6 between the ears 8 thereon 15 and is adapted to engage the front end wall 12 of the drum. The half bearings 5 and 6 thus receive the screw-threaded end of the ram to securely fasten the drum to the end of the ram, said end of the ram being received within the drum and thus said drum 20 may be quickly attached to or detached from the end of the ram without the necessity for screwing it in place by rotative movement of the drum relative to the ram, the half bearing on the drum being simply engaged with the end of the ram and then the movable half bearing moved downward into engagement with the ram to interlock the threads on the ram and bearing parts, and 25 then by tightening up the nuts on the studs 7 and bolts 9 the two halves of the bearing are clamped firmly about the end of the ram and the screw-threads drawn into interlocking engagement to firmly and rigidly hold the 30 drum in place upon the ram and against rotative movement relative thereto. Quick detachment of the drum from the ram is effected by loosening the nuts on the studs 7 and bolts 9, when the upper half of the bearing may be moved upwardly a sufficient distance to disengage the threads, and the drum 35 slipped from the end of the ram.

The outer rim or circular wall 13 of the drum 4 is provided with an annular outstanding rib 14 and a suitable carrying frame or head 15, which is of circular outline to correspond with the circular formation of the drum, is provided with an outstanding annular end flange 16 having an 40 internal diameter corresponding with the external diameter of the drum 4 to fit over said drum, and the end wall 17 of this supporting frame or head is adapted to lie parallel with the face of the wall 12 of the drum, with the outer end of the flange 16 abutting the rib 14 on the drum. To lock the supporting frame 15 in place upon the drum, a split ring 18 is provided having an inwardly extending annular flange 19 to engage one side of the rib 14 and this ring is internally screw-threaded to engage the screw-threaded outer face of the flange 16. By turning the ring 18, the frame 15 is 45 drawn toward the drum and the flange 16 brought into firm frictional engagement

with the rib 14, and then by tightening the nuts 20 upon the ends of a clamping bolt 21 which passes through openings in lateral ears 22 adjacent the divided ends of the split ring 18, said ring is drawn into close 50 frictional and clamping engagement with the flange 16 on the frame 15 and with the drum 4. The supporting frame 15 being thus mounted upon the cylindrical outer surface of the drum 4, may be rotated relative to the drum and ram 3 by loosening the bolt 21 and opening the split ring 18 slightly so that the frame and ring will turn freely upon the drum. The supporting frame 15 which carries the cutting tools as herein-after described, may therefore be rotated upon the drum 4 to bring any one of the cutting tools into operative position and this adjustment may be quickly effected, 55 thus facilitating the operation of changing tools to perform a series of different operations upon the work, these several tools being set up in the head to perform the several operations upon the work in hand, and retaining their setting so that it is unnecessary to reset the tools for each operation upon each piece of work when a large number of pieces are to be machined in a like manner.

In the frame member or supporting head 15, is provided a transverse T-slot or guide way 23 extending transversely of the head near the lower side thereof and in this slot two blocks 24 are mounted to slide therein, and secured to each block is a supporting plate or member 25 having a plane outer face against which the inner face of a supporting plate 26 engages, said plates 25 and 26 being detachably and adjustably secured together by a bolt 27 passing through an opening in the plate 25 and through an elongated slot 28 in the plate 26 located in an upward extension of the plate. A clapper box 29 which is of rectangular form in cross-section is sleeved upon an outwardly projecting stud 30 on the outer face of the plate 26, said stud being of rectangular form in cross-section to fit within the opening of the clapper box, which box is pivotally attached to the stud by a pin 31 passing through 110 openings in the sides of the box and through an opening in the stud near the upper and outer corners of the box.

The plate 25 is detachably secured to the block 24 and the plate 26 with its stud 30 115 is secured to the plate 25, by means of a bolt 32 extending through openings in the block, plates and stud and is provided with a head 33 (shown in dotted lines in Fig. 4) at its inner end to engage a recess in the back of the block 24 and with a nut 34 on its outer end to engage the outer side of a plate 34^a which is held by the nut and bolt firmly against the end of the stud 30 with the edges of said plate overlapping the end of 120 125 130

the clapper box to limit the swinging movement of the box in one direction. The bolt 32 therefore forms means for securing the plate 25 to the block 24 and 5 also for pivotally securing the supporting plate 26 to the plate 25. The lower side of the stud 30 is relieved or cut away within the clapper box to permit of a slight swinging movement of the clapper box upon the 10 stud about its pivot 31 and in each side of this clapper box is formed a groove or channel 35 to receive a cutting tool 36, said tool being of rectangular form in cross-section and fitting within either groove, 15 and to hold the tool in place in its groove, set screws 37 are provided to engage the forward edge of the tool and securely clamp it within its groove or channel in the side of the clapper box. To normally 20 hold the clapper box turned upon its pivot and in a vertical position, a flat leaf spring 38 is provided, said spring being secured to the lower side of the stud 30 within the space formed by cutting away this lower 25 side of the stud and the free end of this spring is arranged to ride upon the inner face of the lower wall of the clapper box to exert a pressure thereon for swinging the box upon its pivot. The tool 36 may be 30 placed in the groove or channel 35 at either side of either clapper box, and as these clapper boxes are each carried by a separate slide comprising the block 24 and plate 25, which slides are movable transversely of the 35 head within the guide ways 23, said clapper boxes may be moved toward or from each other to adjust the tools relatively and relative to the vertical center line of the head. When it is desired to bring the tools close 40 together, they may be removed from the holding grooves in the outer sides of the clapper boxes to the grooves in the inner sides thereof and tools of a suitable form provided to perform a particular operation, 45 such as cutting a deep narrow groove or facing the bottom and side walls of such a groove. When the tools are set for facing the side walls of a groove, it is necessary, in order to provide a clearance, that these tools 50 be set at a slight inward incline toward each other and this setting is accomplished by slackening the nuts on the bolts 27 and swinging the supports for the clapper boxes, comprising the plates 26 and studs 30, upon 55 the bolts 32 relative to the supporting plates 25. In a like manner, the tools may be given a reverse slant when employed in facing the outer side faces of an upstanding rib or wall on the work or other parallel 60 side faces which it is desirable to face off. As the head is applied to the ram of a draw-cut shaper, the working stroke is horizontal and inward or toward the frame 1 of the machine, and to relieve the drag of the tool 65 upon the outward stroke of the ram, the

clapper boxes are pivotally supported, as previously described.

To facilitate the accurate adjustment of the tools toward and from each other, right and left hand screws 39 are provided as 70 shown in Fig. 2 between the adjacent sides of the members 25 to space the slides comprising said members and their blocks 24, apart and thus accurately space the tools carried thereby. This tool carrying head is 75 particularly adapted for use in machining large castings, such as locomotive drive boxes, where it is necessary to finish parallel surfaces, plane off horizontal surfaces, finish the sides and bottoms of grooves or ways, and perform a number of similar operations 80 upon the same piece of work, as one or more surfaces may be finished at the same time and the tools quickly and easily adjusted or changed to perform the several operations. 85

It is necessary, however, in performing certain operations, to use a single tool and in order that a single tool may be used without the necessity for removing the entire head from the ram and substituting another therefor carrying a single tool, a third clapper box 40 is provided for holding a single tool with the tool extending radially of the axis of the head, said clapper box being pivotally supported adjacent one corner thereof upon a pivot pin 41 extending through the box and through openings in a pair of parallel ears 42 which are formed integral with the frame or carrying member 15 adjacent the side thereof opposite that at which the transverse way 23 is located, said ears extending outwardly from the outer side of the frame. This clapper box 40 has a central rectangular opening to receive the tool 42^a which is held in place 95 therein in any suitable manner, as by a set screw 43 and to hold the clapper box turned upon its pivot into engagement with an abutment bar 44, a coiled spring 45, Fig. 3, 100 is set within a recess in the frame 15 to bear against the inner side edge of the clapper box. The abutment bar 44 is secured by bolts 46 to the outer ends of the ears 42, spanning the space between the ears within 105 which the clapper box rotates, and thus the cutting strain on the tool is taken by the abutment bar and upon the return or idling stroke, the clapper box is free to rotate upon its pivot sufficiently to relieve the drag on 110 the point of the tool. 115

When it is desired to use a single tool in performing a certain operation upon the work, it is unnecessary to remove the entire head from the ram and substitute another therefor carrying a single tool, as the single tool 42^a may be readily brought into operative position by rotating the carrying frame 15, as previously described, upon the drum 4. By a proper setting of the rotatable carrying frame 15 relative to the drum, the 120 125 130

tool may be given the desired lateral inclination to perform the work in hand.

To accurately hold the frame 15 in any one of the several positions to which it may be rotated to position the tools in the desired relation to the work, a plunger 47 (Fig. 8) is mounted in a bore 48 provided therefor on the wall 17 of the frame or carrying member 15 to project through said wall into engagement with a bushed socket 49 in the wall 12 of the drum 4, said plunger and socket being tapered to provide for accurate location and firm holding of the frame relative to the drum. A stem 50 is provided on the plunger, which stem extends outwardly through the bore with a coiled spring 51 sleeved thereon between the plunger and a cap member 52 closing the outer end of the bore, said spring exerting a force to normally hold the plunger projected into its socket, and said cap 52 is formed with a transverse V-notch 53 in its outer face to receive a pin 54 carried by the stem 50 and extending transversely thereof. By turning the stem 55 by means of the handle 55 on its outer end, the ends of the pin 54 are caused to ride up the sides of the V-groove, thus moving the stem endwise against the action of the spring 51 and disengaging the plunger from its socket in the wall 12, permitting free turning movement of the carrying frame 15 relative to the drum 4. Any desired number of sockets 49 properly positioned in the wall 12 may be provided to provide for holding the frame in the several positions for properly positioning the several tools relative to the work.

To frictionally hold the frame 15 against easy turning relative to the drum and also take up all possible lost motion, a friction disk 56 (Fig. 9) is mounted in a recess in the face of the wall 17 to engage the opposed face of the wall 12 and this disk is adapted to be forced into contact with the wall 12 by means of a screw 57 operated by a handle 58 on its outer end.

By providing a tool carrying head, of the character described, applicable to the ram of a draw-cut shaper, a wide range of work may be performed without the necessity for removing the head from the ram and substituting another therefor, and a quick and accurate adjustment of the several tools is facilitated by the arrangement, as the desired tool may be brought into operative position by a rotative movement of the head. Further, the application of the head to the ram and its removal therefrom is greatly facilitated by the employment of a two-part threaded bearing to engage the screw-threaded end of the ram.

While a specific embodiment and application of the invention has been shown and described, it is obvious that changes may be made in the construction and arrangement

of parts, within the scope of the appended claims, without departing from the spirit of the invention and to make the attachment applicable to other heavy duty metal working machines, and I do not therefore limit myself to the particular construction shown.

Having thus fully described my invention, what I claim is:

1. A tool carrying head for metal working machines comprising a drum, a frame 75 rotatively connected to said drum, and a plurality of cutting tools carried by said frame and adapted to be brought into operative position by the rotation of said frame upon said drum.

2. A tool carrying head for heavy duty metal working machines comprising a drum, a tool carrying frame connected to said drum to be rotated thereon, a plurality of cutting tools carried by said frame and extending laterally therefrom to be brought into operative position by a rotative movement of said frame relative to said drum.

3. A tool carrying head for metal working machines comprising a drum, a tool carrying frame connected to said drum to be rotated thereon, means for holding said frame in the position to which it is rotatively adjusted relative to said drum, a pair of tool carrying members adjustably secured to the frame to hold the tools in operative relation with said tools extending laterally of said frame, and a tool carrying member on said frame for carrying a tool with the tool extending radially of the axis of rotation 100 of the frame, said tool or said pair of tools being adapted to be brought into operative position by rotative movement of said frame in relation to said drum.

4. A tool carrying head for attachment 105 to the end of a shaper ram, said head comprising a drum having a half bearing, a half bearing to oppose the half bearing on the drum, said half bearings being internally screw-threaded to engage a screw-threaded end of a ram, means for securing the half bearings together to clamp the end of the ram, and cutting tool carrying means carried by the drum.

5. A tool carrying head as characterized 115 in claim 4, and wherein the half bearing which opposes the half bearing on the drum, is adjustably secured to the drum to be adjusted thereon toward and from the half bearing on the drum.

6. A tool carrying head for metal working machines including a circular drum, means for detachably securing the drum in operative position upon the machine, a carrying frame having an externally screw-threaded flange to fit over the drum and turn thereon, locking means for holding the frame upon the drum and in the position to which it is rotatively adjusted, comprising an internally screw-threaded ring having an inwardly

extending flange to engage the drum, a plurality of cutting tools carried by the frame adapted to be brought into operative position by rotation of the frame upon the drum, and means carried by the frame to lock the same in the several positions to which it may be turned for holding the tools in operative position.

7. A tool carrying head for heavy duty metal working machines comprising a drum, means for detachably securing the drum in operative position upon the machine, an outwardly extending annular rib on the drum, a tool carrying frame having an annular flange to fit over the drum with the end of the flange in abutting relation to said rib on the drum, said flange being externally screw-threaded, a split ring having an internal screw-thread to engage the screw-thread of the flange and formed with an inwardly extending flange to engage the side of the rib on the drum opposite that engaged by the flange on the frame, means for drawing the ends of the split ring toward each other to clamp the same about the drum and flange on the frame, a pair of tool carrying members positioned upon the outer side of the frame adjacent one side thereof and adapted to hold cutting tools with the tools extending laterally of the head, a third tool carrying member positioned upon the frame adjacent the side of the frame opposite that at which the pair of tools is located and adapted to hold a cutting tool with the tool extending radially of the axis of rotation of the frame upon the drum, and means on the frame to engage the drum and lock the frame in the position to which it is rotatably adjusted.
8. A head for metal working machines comprising a circular drum having an end wall, means on the drum for detachably securing the drum to the machine, a carrying frame having a laterally extending annular flange to fit over the drum and turn thereon, a ring mounted on the drum and engaging said flange to hold the frame in position upon the drum and permit rotation of the frame upon the drum, a pair of adjustable tool carrying members, means for adjustably holding said pair of members in position upon the frame, said means including a way in the frame extending transversely therein adjacent one side of the frame, a third tool carrying member on the frame adjacent the side thereof opposite that at which the pair of members is located, said member being adapted to hold a cutting tool with the tool extending radially of the axis of rotation of the frame, a tapered plunger carried by the frame to engage openings in the end wall of the drum, said end wall of the drum being provided with a series of tapered openings to receive said plunger and hold the frame in the several positions to

which it may be rotatively adjusted upon the drum.

9. A tool carrying head for metal working machines comprising a circular drum having an end wall, a carrying frame having a wall confronting the end wall of the drum and provided with an annular externally screw-threaded flange, said flange being of an internal diameter corresponding to the external diameter of the drum to fit thereover and turn thereon, a split ring mounted upon the drum and internally screw-threaded to engage the external screw-thread of the flange for holding the frame in place upon the drum and free to rotate thereon, a transverse way on the frame, carrying plates adjustable in said way, clapper boxes carried by said plates, means for holding said plates and clapper boxes in the position to which they are adjusted upon the frame, a third clapper box mounted on the frame adjacent the side of the frame opposite that at which the way is located, means carried by the frame to lock the frame in adjusted position relative to the drum, and friction means carried by the frame to frictionally engage the drum and resist rotative movement of the frame relative to the drum.

10. A tool carrying head for metal working machines, comprising a drum having an end wall and an outwardly extending annular rib, a frame having a wall abutting the end wall of the drum and provided with a laterally extending annular flange to fit over the drum with the end of the flange abutting the annular rib on the drum, a split ring having an inwardly extending flange to engage the side of the rib opposite that engaged by the flange on the frame, said flange and ring being screw-threaded for engagement with each other, a transverse way on the frame adjacent one side thereof, a pair of clapper boxes, means for adjustably supporting the clapper boxes, said means being adjustable longitudinally of said way, to adjust the clapper boxes transversely of the frame and relative to each other, said carrying means for the clapper boxes each including a supporting bolt upon which each clapper box may be rotatively adjusted, a third clapper box carried by the frame adjacent the side thereof opposite that at which said way is located, said clapper box being adapted to carrying a single cutting tool with the tool extending radially of the axis of rotation of the frame, means for locking the frame to the drum in any of the several positions to which the frame is adapted to be rotated upon the drum to locate cutting tools in operative positions, said means comprising a tapered plug carried within a socket on the frame and adapted to engage openings provided in the end wall of the drum, and means for frictionally resisting the rotation of the frame upon the drum and

for taking up lost motion between the frame and drum, said means comprising a friction plate carried by the frame within the face of the wall opposing the end wall of the drum, and a screw for forcing said friction plate into contact with the end wall of the drum.

11. A tool carrying attachment for metal working machines comprising a drum, a frame rotatively mounted upon said drum, means for holding said frame in the several positions to which it may be rotated upon said drum, clapper boxes adjustably mounted upon said frame and non-rotative metal cutting tools mounted in said clapper boxes.

12. A tool carrying attachment for metal

working machines comprising a cylindrical bearing member, a frame mounted upon said member for rotative movement thereon, a plurality of non-rotative metal cutting tools, means carried by and adjustable relative to said frame for carrying said cutting tools, and means for holding said frame in the position to which it is rotatively adjusted relative to said bearing member. 20

25 In testimony whereof I affix my signature in presence of two witnesses.
